BERT C. WILLIAMS, OF SAN FRANCISCO, CALIFORNIA, ASSIGNOR OF THIRTY ONE-HUNDREDTHS TO FRED B. BAIN, OF SAN FRANCISCO, CALIFORNIA.

AIR-VALVE AND TRAP.

1,226,291.

Specification of Letters Patent. Patented May 15, 1917.

Application filed March 25, 1916. Serial No. 86,659.

To all whom it may concern:

Be it known that I, BERT C. WILLIAMS, a citizen of the United States residing in the city and county of San Francisco and State 5 of California, have invented new and useful Improvements in Air-Valves and Traps, of which the following is a specification.

This invention relates to an air valve particularly constructed for use in connection 10 with steam radiators.

One of the objects of the present invention is to provide an air valve particularly constructed for use in connection with steam radiators, which will not only serve as a 15 vent for the air and permit the escape of a certain amount of steam, but which will also serve as a pressure reducer and a trap for any water which may accumulate from condensation.

20 Another object of the invention is to provide a heat-actuated thermostat control to regulate the flow of steam through the radiator, thereby making it possible to automatically maintain a predetermined temperature 25 in the room, and furthermore, to provide an indicator which is raised to a visible position the moment the trap begins to fill with water.

Further objects will hereinafter appear. 30 The invention consists of the parts and the construction and combination of parts, as hereinafter more fully described and claimed, having reference to the accompanying drawings, in which—

35 Figure 1 is a central, vertical section through the valve.

Fig. 2 is a cross section on line 2—2, Fig. 1.

Referring to the drawings in detail, A 40 indicates the cylinder or barrel of the valve. This cylinder is provided with a similar shaped externally threaded extension 2 for the purpose of permitting the valve as a whole to be connected with a steam radiator. 45 Formed interiorly of the extension is a valve seat 4 for the reception of a valve 5, which is carried by a thermostat 6 mounted interiorly of the extension 2. The valve 5 is in this instance guided, so that perfect alinement with relation to the seat 4 is always maintained. This is accomplished by securing a pin 11 on the point of the valve which extends through the valve seat, indicated at 4.

Secured on the lower end of the casing A 55 is a drain valve 14 and secured on the upper end of the casing is a cap 15 provided with a vent opening 16 and an interior valve seat 17. Mounted interior of the casing is a float, consisting of two sections 18 and 19. 60 The section 19 consists of a tube which is open at the lower end, as indicated at 20. The upper section consists of a float which is provided with a valve 21 at its upper end, the two sections 18 and 19 being rigidly 65 connected to move in unison.

The float as a whole with connected valve 21 is guided interior of the casing to permit a perfect alinement of the valve 21 with relation to its seat 17 by means of lugs 22 70 formed on the interior of the casing or by any other suitable means, and the point of the valve is provided with a pin 23 which is of sufficient length to extend through the cap 15 when the valve 21 is closed. 75

The valve as a whole first of all serves as a vent for the escape of air and a certain amount of steam from the radiator, 2nd:—It serves as a pressure reducing chamber for the steam which is admitted through the 80 valve opening 11', 3rd:—The lower end of the casing serves as a trap for any water which may escape from the radiator or accumulate by condensation, and 4th:—The provision of the thermostat provides a 85 means for regulating the escape of air and steam from the radiator, thus providing a means for automatically maintaining a predetermined temperature. The operation will be as follows: 90

With the valve as a whole connected with the radiator and with valve 5 open, it will be seen that steam or air will be permitted to escape through the passage 12 and the valve opening 11' into the interior of the 95 casing A, it is then permitted to escape through the vent 11' controlled by the valve 5. The pressure of steam admitted through this opening is thus instantly reduced and any whistling sound is eliminated, as the 100 escaping air passing through the vent 16 will not have sufficient velocity. The steam, however, immediately heats the disks of the thermostat and will thus cause these to expand and close the valve, only a small 105 amount of the steam is thus permitted to escape. The valve will thus remain closed until the steam temperature in the radiator

and the passage is decreased sufficiently to permit the disks in the thermostat to contract. The valve will then again open and permit either a small amount of air or steam 5 to escape and will again be closed the moment the temperature is sufficiently increased to expand the disks and close the valve. A predetermined temperature suitable for a room or for other installations is thus 10 automatically maintained at all times without any regulation or adjustment on the part of an operator.

Any condensation of steam or water escaping from the radiator will drain and accumulate in the lower end of the casing. The water thus accumulated will instantly rise in the trap and finally cause the float to rise and close the valve 21. The pin 23 will then project through the cap 15 and will 20 thus display a warning which indicates that the trap is filled with water and should, therefore, be drained by opening the valve 14. No steam or water can escape from the valve casing A when the valve 21 is closed, 25 thus making it impossible for any water to escape through the vent 16 and ruin the carpets or floors.

The device as a whole is simple and compact in construction; it not only serves as an 30 automatic regulator as far as the temperature of the room is concerned, but also serves as a pressure reducer which prevents the annoying whistling sound generally emitted from most types of radiator valves, it further 35 serves as a trap for any condensation of water and is provided with a valve 14 to permit the water to be drained when a visible indication is given by the projected position of the pin 23.

40 The materials and finish of the several parts of the device may otherwise be such as the judgment and experience of the manufacturer may dictate.

I wish it understood that various changes 45 in form, proportions and minor details of construction may be resorted to within the scope of the appended claims, and that I

do not wish to limit myself to the specific design and construction here shown.

Having thus described my invention, what 50 I claim and desire to secure by Letters Patent is—

1. In a pressure controlling trap of the character described, a vertical tubular chamber and a horizontal member extending from the center of one side, a valve opening from said member into the side of the first-named chamber, a valve controlling said opening and a thermostat located behind said valve, a float in the main chamber, a valve carried 60 by the upper end of the float, and a controlled outlet at the bottom of the chamber.

2. An air and pressure controlling trap, consisting of vertical and horizontal tubular united chambers, the vertical chamber having an escape passage and valve seat at the top, a two-part float in said chamber and a valve carried by the upper end of the float, a valve controlled opening from the horizontal chamber to the vertical one, connection from the horizontal chamber to a radiator, and a thermostat located between said inlet and the valve. 65

3. An air and vapor pressure controlling trap, comprising a horizontal chamber connected at one end with the source of pressure, a guided valve closable upon a seat at the opposite end and a thermostat contacting with the base of the valve, a vertical chamber with the side of which the first named 70 valve opening connects, a two part float having a valve at its upper end and an opening and valve seat, with which said valve co-acts, a controlled discharge passage at the 75 bottom of the chamber, and guides formed 80 in the sides of the chamber to control the movements of the float and its valve. 85

In testimony whereof I have hereunto set my hand in the presence of two subscribing witnesses.

BERT C. WILLIAMS.
